[57] **CLAIM**

The ornamental design for a battery operated toothbrush, as shown and described.

DESCRIPTION

FIG. 1 is a perspective view from the right side of a battery operated toothbrush showing my new design;

FIG. 2 is a left side elevational view thereof, the right side elevational view being a mirror image thereof;

FIG. 3 is an elevational view as seen from the front thereof;

FIG. 4 is an elevational view as seen from the back thereof;

FIG. 5 is an elevational view as seen from the head end thereof;

FIG. 6 is an elevational view as seen from the handle end thereof;

FIG. 7 is a perspective view from the right side of a second embodiment of the design shown in FIGS. 1-6;

FIG. 8 is a left side elevational view thereof, the right side elevational view being a mirror image thereof;

FIG. 9 is an elevational view as seen from the front thereof;

FIG. 10 is an elevational view as seen from the back thereof;

FIG. 11 is an elevational view as seen from the head end thereof; and,

FIG. 12 is an elevational view as seen from the handle end thereof.

The broken line showing of bristles in FIGS. 7, 8, 9 and 11 is for illustrative purposes only and forms no part of the second embodiment.
